COMBINATION SCREWDRIVER AND ELECTRICAL TESTER

Kenneth A. Hopkins, Farmington, Mich., assignor to Marfree, Inc., Detroit, Mich.

Filed Aug. 2, 1967, Ser. No. 8,098

Term of patent 14 years

(Cl. D93—4)

FIG. 1

I claim:

The ornamental design for a combination screwdriver and electrical tester, as shown.
